ROLLER SKATE

Filed April 25, 1947

UNITED STATES PATENT OFFICE

2,557,233

ROLLER SKATE

Vincent J. Power, Garden City, Kans.

Application April 25, 1947, Serial No. 743,823

2 Claims. (Cl. 280—11.23)

1

This invention relates to a roller skate, and more particularly to a roller skate of the shoe-attached, two-wheel style.

A primary object of this invention is the provision of an improved two-wheeled roller skate characterized by increased strength in mounting of the wheels, and having a metal housing adapted to be attached to the sole plate for increasing the strength of the construction.

An additional object of the invention is the provision of improved wheel mounting for such a skate characterized by means whereby side drag on the wheels will not disalign the same.

A further object of the invention is the provision of such a skate which is sturdy and durable in construction, reliable and efficient in operation, and relatively simple and inexpensive to manufacture, assemble and utilize.

Other objects will in part be obvious and in part be pointed out as the description of the invention proceeds, and shown in the accompanying drawings, wherein there is disclosed a preferred embodiment of this inventive concept.

In the drawings:

Figure 1 is a side elevational view of one form of skate embodying features of the instant invention, shown as applied to a skating shoe.

Figure 2 is a bottom plan view of the construction shown in Figure 1.

Figure 3 is a sectional view taken substantially along the line 3—3 of Figure 1, as viewed in the direction indicated by the arrows.

Figure 4 is a fragmentary, longitudinal, vertical, sectional view taken in line 4—4 of Figure 2, parts omitted;

Figure 5 is an enlarged, fragmentary plan view of the bottom of the housing and illustrating a slot formed therein.

Similar reference characters refer to similar parts throughout the several views of the drawings.

Referring now to the drawings in detail, there is generally indicated at 10 a skate shoe of any desired conventional type, provided with a sole plate 11. Adapted to be secured to the sole plate 11 is a housing 12 of generally V-shaped cross-sectional area, as best shown in Figure 3. The housing 12 is provided with a peripheral flange 13, adapted to be secured, as by bolts or rivets 14, to the sole of the shoe, the upper portion of the housing 12 conforming in general outline to the sole 11 of the shoe. The V-shaped housing 12 is provided in its bottom and at its transverse center with forward and rear longitudinally spaced, elongated slots 15, which extend longi-

2

tudinally of the housing, as shown. The opposite side edges of the slots 15 have laterally, oppositely arranged notches 16 formed therein, and the notches are arranged at the longitudinal centers of the slots 15.

Pairs of ball bearings 18 are provided, and arranged adjacent to the notches 16 and have their upper portions extending into the notches and above the bottom of the housing 12, Figure 1. 10 Short, transverse axles 19 are secured within the inner races of the ball bearings 18, and forward and rear wheels 20 are mounted upon the axles 19 and arranged between the ball bearings for free rotation with the axles 19. The upper portions of the wheels 20 project upwardly through the narrow slots 15 and into the housing 12, as shown. The tops of the wheels 20 are disposed near and spaced below the sole plate 11. The wheels 20 include transversely curved, peripheral flanges 21, having tires 22 of hard rubber, synthetic rubber or the like, mounted thereon. The bearings 18 and associated elements are rigidly connected with the housing 12 by means of pairs 15 of upper, arcuate bearing sections or straps 23 having their upper portions mounted within the notches 16 and projecting above the bottom of the housing 12, as shown. The inner, longitudinal edges of the upper pairs of bearing brackets 23 are disposed flush with the opposite longitudinal edges of the slots 15, Figure 2, and the upper bearing brackets 23 of the pairs are transversely aligned. The pairs of upper bearing brackets 23 are permanently rigidly secured to the bottom of the housing 12 and within the notches 16 by welding or the like, and the upper bearing brackets include forward and rear, horizontally disposed lugs 24, provided with screw-threaded openings 24'. The lugs 24 project a slight distance below the bottom of the housing 12. The top portions 30 of the ball bearings 18 engage within the upper arcuate bearing brackets 23, and pairs of bottom arcuate bearing brackets or straps 25 engage about the bottoms of the outer races of the ball bearings for clamping the ball bearings securely 35 in place between the upper and lower bearing brackets. The bottom bearing brackets 25 include forward and rear apertured ears or lugs 27 receiving screws 28 which engage in the screw-threaded openings 24' of the upper bearing brackets 23 for rigidly clamping the outer races of the ball bearing 18 in place between the upper and lower bearing brackets. The lower bearing brackets 25 are disposed bodily beneath the bottom of the housing 12, and the axles 19 are 40 arranged slightly below the bottom of the hous- 45 50 55

ing, both axles being at the same elevation. The wheels 20 are thus freely rotatable both with the inner races of the ball bearings, and substantially the entire upper half of each wheel extends above its associated slot 15 and into the housing 12. The arrangement is highly compact, simplified and extremely sturdy.

From the foregoing, it will now be seen that there is herein provided an improved two-wheeled skate characterized by a mounting of material rigidity, due to the fact that the wheels are borne solely by the metallic housing 12, which obviates disalignment of the skate wheels upon side drag thereon, and which accomplishes all the objects of this invention, including many advantages of great practical utility and commercial importance.

As many embodiments may be made of this inventive concept, and as many modifications may be made in the embodiment thereinbefore shown and described, it is to be understood that all matter herein is to be interpreted merely as illustrative and not in a limiting sense.

I claim:

1. A shoe type roller skate comprising a sole plate secured to the bottom of the shoe, an elongated hollow housing secured to the bottom of the sole plate and extending for the entire length of the sole plate, the hollow housing being substantially V-shaped in transverse cross-section and being of substantially uniform width throughout the entire length of the housing, the housing being provided adjacent to its forward and rear ends and in its bottom with forward and rear longitudinally spaced elongated slots, pairs of laterally oppositely disposed upper bearing brackets arranged upon opposite sides of the slots and secured to the housing and projecting into the housing, pairs of lower removable bearing brackets arranged below the upper bearing brackets and in substantial vertical alignment therewith, fastener means connecting the upper and lower bearing brackets, bearings mounted between the pairs of upper and lower bearing brackets and secured in place thereby, axles journaled within the bearings for rotation, the axles being disposed below the bottom of the housing, and wheels mounted upon the axles for rotation therewith and disposed between the bearings and upper and lower pairs of bearing brackets, the wheels extending through said slots and having their upper portions projecting into the housing above the slots.

2. A shoe type roller skate comprising a substantially flat horizontal sole plate secured to the bottom of the shoe, and elongated hollow housing secured to the bottom of the sole plate

and extending for substantially the entire length of the sole plate, said housing being substantially V-shaped in transverse cross-section and having a substantially uniform width throughout its entire length for forming a box structure, the housing being provided in its bottom and at its transverse center and near its opposite ends with narrow elongated longitudinally spaced slots, the slots extending longitudinally of the housing and being provided in their opposite longitudinal edges with laterally oppositely disposed notches, pairs of laterally oppositely disposed upper arcuate bearing brackets arranged upon opposite sides of the slots and having their top portions positioned within the notches and permanently secured to the housing, the inner opposed edges of the upper bearing brackets being substantially flush with the opposite longitudinal edges of the slots, pairs of lower arcuate removable bearing brackets disposed beneath the upper bearing brackets and adjacent to the opposite longitudinal edges of the slots, said lower bearing brackets being disposed bodily beneath the bottom of the housing, screw means connecting said upper and lower pairs of bearing brackets for clamping the same together, pairs of laterally spaced ball bearings disposed between the pairs of upper and lower bearing brackets and clamped in place between the same, the ball bearings being disposed upon opposite sides of the slots and arranged in axial alignment, transverse axles journaled within the ball bearings for rotation and disposed below the bottom of the housing, and wheels mounted upon the transverse axles for rotation therewith and disposed between the pairs of ball bearings and bearing brackets, the wheels extending through the slots in the bottom of the housing and upwardly into the housing, the tops of the wheels being disposed near the bottom of the sole plate.

VINCENT J. POWER.
